UNITED STATES PATENT OFFICE.

EDWARD C. ANGELL, OF NEW YORK, N. Y., ASSIGNOR TO SINGLE SERVICE BOTTLE CORPORATION OF NEW YORK, OF NEW YORK, N. Y., A CORPORATION OF NEW YORK.

APPARATUS FOR MAKING RECEPTACLES OR CONTAINERS.

1,160,816.

Specification of Letters Patent. Patented Nov. 16, 1915.

Application filed August 20, 1914. Serial No. 857,645.

To all whom it may concern:

Be it known that I, EDWARD C. ANGELL, a citizen of the United States, residing in the borough of Manhattan, in the city, county, 5 and State of New York, have invented new and useful Improvements in Apparatus for Making Receptacles or Containers, of which the following is a specification.

This invention relates to apparatus for 10 making receptacles of paper, such as paraffined paper, for carrying liquids and the like, and which are commonly known as single service packages or containers, in which a sheet of material is rolled into tubular form, preferably conical, with the sides or longitudinal edges overlapping and secured together, the tube being closed at one end to constitute the bottom and the other end the top pinched together or collapsed 15 and secured in such position to close the same.

It is the object of the present invention to provide an apparatus to roll the sheet of material into tubular form with the longitudinal edges or sides overlapping and then to apply a clamping strip thereto to secure said overlapping sides together.

In the drawings accompanying and forming a part of this specification, Figure 1 is a front elevation of my improved apparatus. Fig. 2 is a side elevation looking at the left of Fig. 1. Fig. 3 is a plan view. Fig. 4 is a perspective view of the operative mechanism of the apparatus. Fig. 5 is a perspective view of a portion of the metallic clamping strip to show the manner of providing the clamping prongs thereon; and Fig. 6 is a perspective view of the paper feed mechanism.

Similar characters of reference designate like parts throughout the different views of the drawings.

In the embodiment of my invention illustrated in the drawings, the operative mechanism is carried by a suitable framework (designated in a general way by F). A mandrel or arbor 5 around which a sheet of paper or the like is adapted to be wrapped is fixed to the framework to project forwardly therefrom, this mandrel being circular in cross section and in the form of a truncated cone; that is, it tapers from the rear to the forward end.

A pair of paper supporting flaps 6, 6 are connected to a pair of pivoted arms 7. The

conformation of the flaps is such that each will conform to substantially one-half of the circumference of the mandrel, so that when a sheet of paper carried by the flaps is wrapped around the mandrel it will lie snugly against the same, and the sheet is of such size so that the longitudinal edges or sides overlap. These flaps are actuated by a pair of links 8 pivotally connected to the arms 7 and to one end of a rocker arm 9, 60 the other end of the arm 9 carrying a roll 10 caused to engage with and follow a cam 11 by a spring 12. The cam 11 is fixed to a rotatable shaft 13 driven in a suitable manner from the main driving shaft 14, in 70 the present instance by a sprocket chain 15.

The operation of the machine is automatic and to automatically feed sheets of paper between the paper supporting flaps and mandrel, I provide a vertically adjustable table 16 to support a pile of paper P, said table being guided in its vertical movement by a series of posts 17, in the present instance three in number, engaging in openings in lugs extending laterally from the table; 80 these posts also serving to prevent lateral displacement of the pile of paper. To support the table to have vertical adjustment, a rack 19 is fixed to the bottom thereof, a pinion 20 fixed to a rotatable shaft 21 meshing with said rack. The shaft 21 is continuously rotated by a worm 22 fixed to a shaft 23 meshing with a worm wheel 24 mounted on said shaft 21. The shaft 23 is rotated by a gear 25 fixed thereto meshing 90 with a pinion 26 fixed to the shaft 13. As the paper from which the receptacles are made is relatively thick the table is continuously moving up and the rotation of the shaft 21 is so timed that the top of the pile of paper will be substantially in the same plane at all times as the paper is fed therefrom. To permit the paper table to be lowered the worm 24 is mounted on the shaft 21 to have sliding movement, and by imparting sliding movement to said wheel it is thrown out of mesh with the worm, and the shaft 21 is adapted to have independent rotative movement and the table lowered or adjusted at will.

To intermittently feed the paper between the paper flaps 6 and mandrel, I provide a pair of friction feed rollers 27 located between the paper table and mandrel and mounted to rotate on axes in a plane parallel 110

with the axis of the mandrel and with the 5
axis of the rolls substantially in a plane
with the uppermost sheet of paper on the
pile. These rolls have meshing pinions 28
connected thereto which are operatively
connected to and driven from the shaft 13. To
feed the paper from the pile to the rolls 27,
I provide resiliently supported vertical
fingers 29, in the present instance two in
10 number, the tips of which fingers are pro-
vided with a suitable friction material, such
as rubber. These fingers are slidably sup-
ported by arms 30 adapted to have recipro-
cating movement transverse to the move-
15 ment of the fingers, springs 31 causing the
fingers to resiliently engage with the upper
surface of the top sheet of the pile. The
arms 30 are slidably supported in standard
32 fixed to the framework.

20 To actuate the arms 30 the ends of the
arms opposite to the fingers 29 are connected
by a member 33 connected to a slidably sup-
ported stem 34 having a downwardly ex-
tending forked portion 35 in which engages
25 an offset or inclined portion 36 of a slidably
supported rod 36'. One end of this rod is
connected to one arm of a lever 37 and ac-
tuated by a cam 39 fixed to the shaft 23
with which engages a cam following roller
38 connected to the other arm of the lever.

After a sheet of paper has been fed be-
tween the paper flaps and mandrel and pre-
vious to the flaps folding said paper around
the mandrel a pivoted stop arm 53 is caused
35 to engage with the front end of the mandrel
to prevent the movement of the paper longi-
tudinally of the mandrel and the sheet is
clamped to the mandrel by a clamping plun-
ger 54 supported to have vertical sliding
40 movement in a bracket 55 fixed to the frame-
work. The stop arm 53 is actuated by a
cam 56 on the shaft 13 through a rod 57 con-
nected to the cam and arm, a cam 58 on said
rod coöperating with the clamping plunger
45 54 to cause it to move toward and clamp a
sheet of paper to the mandrel, said plunger
being retracted by a spring 59.

As stated, the overlapped edges or sides of
50 the paper on the mandrel are secured to-
gether by a clamping strip. For this pur-
pose I provide means to intermittently feed
a metallic strip S a predetermined distance
55 adjacent the said overlapped sides of the
paper on the mandrel and provide said strip
with suitable prongs to pass through the pa-
per and be upset to secure said overlapped
sides together. The clamping strip S is car-
ried by a reel 40 rotatably carried by a pair
60 of bracket arms 41 fixed to and projecting
laterally from the framework F. The strip
from the reel passes over a guide roller 42
and between a pair of contacting rollers 43,
44, one of said rollers, as 43, being provided
65 with circumferentially disposed teeth or
projections adapted to engage in circumfer-

entially disposed recesses in the roller 44,
and as the strip is fed by said rollers the
teeth will stamp out and offset a portion
thereof forming prongs 45, as shown in Fig.
5. These prongs are preferably triangular
70 in shape and alternate prongs are offset as
clearly shown in Fig. 5. The roller 43 is driven
from the roller 44 and to actuate the rollers
intermittently a pinion 46 is connected there-
to meshing with a gear 47 rotatably mounted
75 on a stud shaft fixed in the framework.
The gear 47 is rotated and thereby the strip
feeding rolls operated by a pawl and ratchet
mechanism actuated by the main driving
shaft 14, and consisting of a ratchet wheel
80 48 rotatable with the gear 47, a spring in-
fluenced pawl 49 coöperating with said
ratchet wheel pivotally carried by a link 50
hung on the shaft of the gear 47. This link
is connected by a rod 51 to a crank arm 52
85 fixed to and rotatable with the shaft 14. As
the crank is swung upward with the rotation
of the shaft 14, the arm 50 will be lifted, the
pawl riding over the teeth of the ratchet,
and as it swings downward the pawl will en-
90 gage with the ratchet teeth rotating the
ratchet and thereby the gears 47 and rollers
43, 44.

After a predetermined portion of the me-
tallic strip S has been fed and provided with
95 prongs, said clamping strip is caused to
clamp the overlapped edges of the paper
wrapped around the mandrel by a recip-
rocable ram R slidably carried in a head 60
100 forming a part of the framework, said ram
having movement toward and away from
and coöperating with the mandrel to force
the strip prongs through the overlapped
edges of the paper on the mandrel and up-
set said prongs. The alternate prongs on
105 the strip are adapted to be upset or bent
over in opposite directions, and for this pur-
pose the mandrel has an inset 61 projecting
slightly beyond the periphery of the man-
110 drel, the top surface of said inset being be-
veled or inclining slightly from a point sub-
stantially centrally thereof to the sides and
in opposite directions, as clearly shown in
Fig. 1. Just previous to the clamping of the
115 paper on the mandrel by the strip the strip
is severed by a cutter member 62 adjustably
connected to the ram coöperating with a cut-
ter member 63 at the rear of the inset. The
ram is pivotally connected to one end of a
walking beam 73 carried by the head 60 and
120 actuated by a cam 74 on a shaft 75 with
which engages a cam following roller 73' car-
ried by the other end of the walking beam.
The shaft 75 is rotated by the main driving
125 shaft 14 through gears 77 and 78.

After the paper strip has been clamped to-
gether on the mandrel the folding flaps,
clamping plunger 54 and stop arm 53 are re-
leased and the formed tube is pushed off of
the mandrel by an ejector or pusher 64 slid-
130

ably mounted in a slot 65 in the mandrel and connected to a rod 66 slidably mounted in a guide-way 67 on the framework. This ejector is actuated by a segmental gear fixed to the shaft 13 meshing with a pinion 68 to which is connected a crank arm 69 connected by a link 70 to one arm of a pivoted lever 71, the other arm of said lever being connected by a link 72 to the rod 66.

10 The operation of the machine or apparatus is entirely automatic from the feeding of a sheet of paper to the folding flaps to the ejecting of the rolled and clamped tube from the mandrel, the different mechanisms 15 of the apparatus operating successively in proper timed relation. In operation a pile of paper P is first placed upon the paper table 16 and the table adjusted so that the top of the pile is substantially in a plane 20 with the bight of the rollers 27 when the apparatus is set in motion, which may be operated from any suitable source of power, as by a belt 73 passing around a driving pulley 76, and which pulley may also serve 25 as a fly wheel. When the apparatus is set in motion the paper feeding fingers 29 are moved transversely by the arms 30, the rubber tips of said fingers frictionally pulling or pushing the uppermost sheet of paper 30 from the pile to the rolls 27 and by said rolls are fed between the paper supporting flaps 6 and the mandrel and supported by said flaps, said flaps being so constructed as to also serve as a gage for a sheet fed 35 thereto. The clamping plunger 54 moves upward and clamps the sheet to the mandrel and the stop 53 is moved up against the end of the mandrel to prevent the sheet from having motion longitudinally of the mandrel, the plunger 54 and stop 53 moving to 40 said positions simultaneously. The fingers 29 are then returned to normal position and the paper flaps are actuated to wrap the sheet of paper carried thereby around the 45 mandrel with the longitudinal edges or sides overlapping and are retained in this position. After the sheet has been wrapped around the mandrel the mechanism to feed a portion of the clamping strip S adjacent 50 the overlapped sides of the paper on the mandrel and the providing of said strip with clamping prongs is actuated. After the feeding of the strip the ram begins to descend the cutter mechanism first severing 55 the clamping strip and then the ram cooperating with the mandrel to force the clamping prongs on the strip through the overlapped paper and upset said prongs, when the ram is returned to initial position. 60 With the return movement of the ram the folding flaps return to their paper receiving position, and during the return movement of the ram and flaps the stop 53 and clamping plunger 54 are released and the ejector 65 64 is actuated to push the rolled and clamped

sheet which is in the form of a conical tube from the mandrel when the operation is repeated. As already stated the paper table is continuously moving upward and is so timed that the top of the pile is at all times substantially in a plane with the bight of the feeding rolls 27.

Having thus described my invention I claim:

1. In an apparatus of the class specified, 75 the combination of a mandrel; pivoted paper supporting flaps adjacent said mandrel; means to actuate the flaps to wrap a sheet of paper carried thereby around the mandrel with the edges overlapping; means to 80 feed a clamping strip a predetermined distance adjacent the overlapping edges of the paper on the mandrel; a reciprocable ram coöperating with the mandrel to cause the clamping strip to clamp the edges of the 85 paper together; and a cutter carried by the ram to sever the clamping strip.

2. In an apparatus of the class specified, 90 the combination of a mandrel; pivoted paper supporting flaps operable to wrap a sheet of paper carried thereby around the mandrel with the edges overlapping; means to feed a metallic clamping strip a predetermined distance adjacent the overlapped edges of the paper on the mandrel 95 and provide said strip with prongs; a reciprocable ram coöperating with the mandrel to force the strip through the overlapped edges of the paper and upset said prongs to clamp the edges of the paper together; and a cutter to sever the clamping strip. 100

3. In an apparatus of the class specified, 105 the combination of a mandrel; pivoted paper supporting flaps operable to wrap a sheet of paper carried thereby around the mandrel with the edges overlapping; means to feed a metallic strip a predetermined distance adjacent the overlapped edges of the paper on the mandrel and provide said strip with prongs, comprising a roll having circumferentially disposed teeth and a roll contacting with the first roll having circumferentially disposed openings in which the teeth on the first roll are adapted to engage; a reciprocable ram coöperating with the mandrel to cause the clamping strip to clamp the edges of the paper together; and a cutter carried by the ram to sever the 110 clamping strip. 115

4. In an apparatus of the class specified, 125 the combination of a mandrel; pivoted paper supporting flaps operable to wrap a sheet of paper carried thereby around the mandrel with the edges overlapping; a vertically adjustable table for a pile of paper; means to feed a sheet of paper from said table between the mandrel and paper supporting flaps; means to feed a clamping strip a predetermined distance adjacent the 130

overlapping edges of the paper on the mandrel; a reciprocable ram coöperating with the mandrel to cause the clamping strip to clamp the overlapped edges of the paper together; and a cutter to sever the clamping strip.

5. In an apparatus of the class specified, the combination of a mandrel; pivoted paper supporting flaps operable to wrap a sheet of paper carried thereby around the mandrel with the edges overlapping; means to feed a clamping strip a predetermined distance adjacent the overlapped edges of the paper on the mandrel; a reciprocable ram coöperating with the mandrel to cause the clamping strip to clamp the overlapped edges of the paper together; a cutter to sever the strip; and a pusher movable longitudinally of the mandrel to engage with and 20 push the clamped paper from the mandrel.

6. In an apparatus of the class specified, the combination of a mandrel; a pair of hinged paper supporting flaps adjacent said mandrel; means to feed a sheet of paper to said flaps; a clamping member to coöperate with the mandrel to hold the paper in position on the mandrel; a pivoted stop to prevent endwise movement of the paper on the mandrel; means to operate the paper supporting flaps to wrap the paper around the mandrel with the edges overlapping; means to feed a clamping strip a predetermined distance adjacent the overlapped edges of the paper on the mandrel; a reciprocable ram coöperating with the mandrel to cause the clamping strip to clamp the edges of the paper together; a cutter carried by said ram to sever the clamping strip; a pusher movable longitudinally of the mandrel to engage with and push the clamped paper from the mandrel; and means to release the pivoted stop and the clamping member previous to the pushing of the clamped paper from the mandrel.

45 7. In an apparatus of the class specified,

the combination of a mandrel; means to support and wrap a sheet of material around the mandrel with the edges overlapping; means to feed a metallic strip adjacent the overlapped edges of the material on the 50 mandrel and provide said strip with prongs; and a ram coöperating with the mandrel to force the strip prongs through the overlapped material and clamp it together.

8. In an apparatus of the class specified, 55 the combination of a mandrel; means to support and wrap a sheet of material around the mandrel with the edges overlapping; means to intermittently feed a metallic strip adjacent the overlapped edges of the material on the mandrel and provide said strip with prongs, comprising a pair of rolls one 60 roll having projections and the other roll recesses in which the projections engage as the rolls are rotated; and means to sever the strip and force the strip prongs through the overlapped material to clamp the same together.

9. In an apparatus of the class specified, the combination of a mandrel; means to 70 support and wrap a sheet of material around the mandrel with the edges overlapping; means to feed a metallic strip adjacent the overlapped edges of the material on the mandrel and provide said strip with prongs, 75 comprising a pair of rotatable rolls one roll having circumferentially disposed prongs and the other roll recesses in which the prongs engage; means to intermittently actuate the strip feeding means; means to 80 sever the strip during the intervals of rest; and a reciprocable ram coöperating with the mandrel to force the prongs on the severed strip through the overlapped material to clamp the same together.

EDWARD C. ANGELL.
